Attorney

UNITED STATES PATENT OFFICE.

HARVEY LESTER WATKINS, OF PHILADELPHIA, PENNSYLVANIA.

BOTTLE-CAP.

1,304,002.

Specification of Letters Patent. Patented May 20, 1919.

Application filed October 6, 1917. Serial No. 195,061.

To all whom it may concern:

Be it known that I, HARVEY LESTER WATKINS, a citizen of the United States, residing at Philadelphia, in the county of Philadelphia and State of Pennsylvania, have invented certain new and useful Improvements in Bottle-Caps, of which the following is a specification.

This invention relates to bottles and jars and it is the principal object of the invention to provide a highly efficient and simple closure capable of being used in connection with various forms of containers and serving as means for positively sealing the same. It is the more specific object of the invention to provide a closure cap having yieldable engaging portions whereby the cap when inserted in a bottle or jar neck will be permitted to instantly engage the adjacent surfaces and thus secure itself in position.

The improvements in the details and arrangement of parts will be apparent from an inspection of the accompanying drawings, in connection with the specific description hereinafter contained, and wherein the preferred embodiment of the invention is disclosed for the purpose of imparting a full understanding of the same.

In the drawings:—

Figure 1 is a top plan of the improved closure;

Fig. 2 is a vertical section therethrough;

Fig. 3 is a vertical section showing the cap arranged in a bottle neck.

Having more particular reference to the drawings and in connection with which like reference characters will designate corresponding parts in the several views, B represents the bottle or jar neck in which the improved closure cap is inserted. The closure cap in its preferred form includes an annular body portion 1 having a vertically disposed flange 2 formed upon the marginal extremities thereof, which flange is bent upon itself intermediate the ends thereof to provide an obliquely disposed secondary flange 3, clearly shown in Fig. 2. In normal position, the obliquely disposed secondary flange 3 assumes a position as shown in Fig. 2 and inasmuch as the annular body portion 1 is of a size to be snugly received in a bottle neck, the secondary flange 3 will be placed under considerable pressure when

engaged with the adjacent surfaces of the neck of the bottle, thereby causing the annular body portion to bulge slightly as indicated by the numeral 4.

It is to be understood that the improved closure cap may be formed of any suitable material, such as metal, cardboard, fiber-board or the like. When the caps are formed of metal, the inherent resiliency thereof will serve as means for causing the secondary flange 3 to be positively engaged with the inner surface of a bottle or jar neck when inserted therein. However, when the closures are formed of paper or similar material, the outer surface of the secondary flange 3 may be and preferably is coated with a suitable adhesive substance, which substance may be moistened previous to the introduction of the cap into the bottle or jar neck. When once inserted in a bottle or jar neck the adhesive coated side of the secondary flange 3 will positively engage the inner surface of the same, and consequently, serve as an efficient and positive closure and seal therefor.

It will be readily understood, that my improved closure cap may be used in connection with practically any form of container, such as condiment or preference may dictate. When formed of paper or like material, the device will form an efficient closure for vegetable preserving jars or jelly glasses and the like. When formed of metal or like material, the closure may be not only used for the above mentioned purposes, but also adapted for use in connection with practically any form of bottle.

Manifestly, the construction shown is capable of considerable modification and such modification as is within the scope of my claims, I consider within the spirit of my invention.

I claim:—

1. A closure cap comprising an annular body portion, a vertically disposed flange formed on said body portion and bent intermediate its ends to provide an obliquely disposed secondary flange.

2. A closure cap comprising an annular body portion formed of spring material and adapted to be snugly received in a container, a vertically disposed flange formed about the body portion, said flange having the intermediate portion of the same bent

to provide an obliquely disposed secondary flange.

3. A closure cap, comprising an annular flexible body portion having a vertically disposed flange formed upon the marginal portions thereof, said flange being bent intermediate its ends to provide an obliquely dis-

posed secondary flange, the outer surface of the secondary flange being coated with an adhesive material.

In testimony whereof, I affix my signature hereto.

HARVEY LESTER WATKINS.
